United States Patent Office.

D. S. HUMPHREY, OF EAST TOWNSEND, OHIO.

Letters Patent No. 73,011, dated January 7, 1868.

IMPROVEMENT IN FIELD-FENCE.

The Schedule referred to in these Letters Patent and making part of the same.

TO ALL WHOM IT MAY CONCERN:

Be it known that I, D. S. HUMPHREY, of East Townsend, in the county of Huron, and State of Ohio, have invented certain new and useful Improvements in Field-Fences; and I do hereby declare that the following is a full and complete description of the same, reference being had to the accompanying drawings, making a part of this specification, in which—

Figure 1 is a side view of the fence.

Figure 2 is a top view.

Like letters of reference refer to like parts in the views.

This fence consists of the posts A A, fig. 1, which are set in the ground in the ordinary way, and at distances varying from twenty to forty feet. To these posts are secured, in parallel lines, two or more wires, B, by means of a hook spike, C, which, on being driven into the post, clamps the wire as would a staple, and thereby holds it firmly and securely in place. To these wires are attached light pickets or slats D, by the employment of a similar spike to that used in fastening the wire to the posts. These spikes are first partially driven into the pickets at the proper place, which are then hung upon the wires the required distance apart. The spike is then driven in up to the head or hook, and then clinched down upon the opposite side. By this means the picket is easily, neatly, and securely fixed to the wires, as shown in fig. 1, and in which it will be seen that long and short pickets may be used alternately with each other. When pickets of unequal length are used, three wires are needed, as shown at A'. This style of fence makes a close bottom with a light, open top. For pickets of equal length two wires only are needed, as shown at B', unless the fence is required to be of unusual strength, in which case three wires may be used, as shown at C'.

If the posts are set long distances apart, it is proposed to support the fence between them, by allowing one or more of the slats to descend to the ground, and rest upon stones or blocks of wood, and thereby sustain the weight of the fence between the posts.

When the line of fence is completed, one or more furrows of earth are turned against each side of the base of the fence, forming thereby a ridge, E, for the purpose of raising up the ground under the fence, so that it may be high and dry.

In the use of wires in the construction of fences, it has been found that in consequence of the contraction of the metal, caused by the changes in the temperature of the season, the wires are very liable to break or tear away from their fastenings; hence, to meet this contraction of the wires, and thereby save them from these accidents, it is proposed to meet this shortening up of the wires by a compensating medium, obtained by bending them at the point immediately encircled by the hook of the spike, as indicated by the dotted lines a, fig. 2. This is done by driving the spike or hook so hard upon the wire as to bend it and sink it slightly into the pickets. This deflection of the wire compensates for this shortening up by straightening, and thus adding to its length, thereby relieving the posts from the great strain which would be exerted upon them by the contraction of the wire; hence they will not break nor tear away from their fastenings. Another purpose is served by this bending the wire, as above described, viz, the wire on being bent is set into the wood, which will contribute to prevent the pickets from any lateral displacement, thereby rendering the slats more secure in their place.

What I claim as my improvement, and desire to secure by Letters Patent, is—

The combination of two or more wires, B, with the posts A and slats or pickets D, when secured thereto by means of the hook spikes C, as specified.
